UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR THE EXTERIOR OF A HOUSE.

SPECIFICATION forming part of Design No. 20,089, dated August 12, 1890.

Application filed July 15, 1890. Serial No. 368,852. Term of patent 7 years.

To all whom it may concern:

Be it known that I, ANTOINE LACROIX, Jr., of the city of Brooklyn, in the county of Kings and State of New York, have invented and 5 produced a new and original Design for the Exterior of a House, of which the following is a specification, reference being had to the accompanying drawings, forming a part thereof.

Figure 1 represents a perspective view of a 10 house showing my design. Fig. 2 represents a horizontal section or plan of the first story. Fig. 3 represents a horizontal section or plan of the second story.

Similar letters of reference designate corresponding parts in all the figures.

A house of this design consists of two stories and an attic third story contained in a sloping roof, an extension projecting from the rear thereof and having a veranda on one side 20 covered by a shed roof, a flat-faced bay projecting from the side thereof and surmounted by a gable roof, a deep octagonal bay to the first and second stories in the front thereof and surmounted by a gable roof, and a veran- 25 da to the first story in front, extending from an entrance - porch in the angle formed by the bay to one side thereof and covered by a shed roof, all as hereinafter more particularly described in detail with reference to the draw- 30 ings.

A B C designate the exterior of the first

and second stories and attic, which are partly contained in an extension D, projecting rearwardly, a portion of which extends for only one story, and is surmounted by a shed roof d, 35 while the main portion takes in the two stories, and at its opposite side has a veranda a at the first story with a hip roof b.

The side of the house has a flat-faced bay E, projecting from the side for two stories, 40 and an attic in a gable roof e, surmounting it.

The front of the house has a deep octagonal bay F to the first and second stories, the gable roof f of which also contains an attic. The main portion of the house is surmounted 45 by a sloping roof G, having a flattened crown g, from which roof the two gabled portions c and f project, an extension in each case of one side of the sloping roof forming one side of the gable. Dormer-windows H, with roofs 50 h, also project from said sloping roof G.

A veranda I, covered by a shed roof i, extends along the front of the house, beginning at one side thereof and terminating with an entrance-porch having a gable roof j. 55

What I claim as my design is—

The design for the exterior of a house, substantially as herein shown and described.

ANTOINE LACROIX, JR.
